UNITED STATES PATENT OFFICE

2,541,333

COMPARTMENTED KEY HOLDER

Henry H. Campbell, Cleveland, Ohio

Application January 24, 1947, Serial No. 724,167

10 Claims. (Cl. 150—40)

1

The object of my present invention has been to produce an improved key holder of the type disclosed by my United States Patent #2,322,920, issued June 29, 1943.

The construction of key holder embodied in said patent involves special advantages by way of provisions including divers key compartments that are provided by the walls of the casing of the holder in conjunction with partition members within the holder, and means for maintaining the exit and entrance portions or openings of the compartments normally closed by resilient spring action, for preventing displacement of keys from the individual compartments in which they are arranged. Other provisions of the patented construction, which by my present invention is improved upon, include features enabling manipulation of the holder and particularly the casing structure thereof, while held in one hand, so that by the exercise of mere compressive force upon the casing at the edges thereof, and using a finger of the hand for selecting a compartment to be controlled for opening, any selected one of the keys in the various compartments may be projected from its particular compartment by a mere flipping of the holder bodily under such manipulation and finger selection action.

According to my present improved construction, I have provided certain novel spring elements contained within the holder, which maintain the casing of the holder substantially under tension so that the exit and entrance portions of the various compartments thereof will normally remain closed to prevent the key in a particular compartment, or in fact the keys in all of the compartments, from being displaced except under authorized conditions.

My invention further involves novel provisions in regard to the manner of formation of the partition elements, one or more of which may be provided in the casing for dividing the holder into the various key compartments at latterly spaced portions intermediate the partitions and sides of the holder, said compartments leading to openable resilient or flexible mouth portions at the opposite ends of the holder casing.

My invention further involves other details of construction including primarily the means for attaching the said spring parts to the casing body, the means for attaching the keys to the spring parts so that the keys may be contained properly in their individual separate compartments, and features of general assembly of the various parts of the holder giving rise to manu-

2

facturing advantages enabling the production of the holder at a relatively cheap cost.

The construction of the detailed improvements above referred to will be clearly understood upon reference to my issued patent hereinbefore identified, in conjunction with the following detailed description and the drawings annexed hereto, in which drawings:

Figure 1 is a side elevation of a holder embodying the general features of my invention.

Figure 2 is an edge view of the holder.

Figure 3 is a view similar to Figure 1 but looking toward the opposite side of the holder.

Figure 4 is a vertical sectional view through the holder and taken about on the line 4—4 of Figure 6.

Figure 5 is a view similar to Figure 4 but with the section taken about on the line 5—5 of Figure 6.

Figure 6 is a vertical plane section of the holder.

Figure 7 is a greatly enlarged end view of the holder with a portion thereof broken away and shown in section to bring out more clearly the manner of attaching the intermediate partition member to the end plates to which the springs which produce tension edgewise in the holder are secured.

Figure 8 is an end view similar to Figure 7 illustrating the holder of a size, substantially, that which will normally be used, and without the sectional illustration afforded by Figure 7.

Figure 9 is a plan view of one of the intermediate partitions in the holder and showing the extension formation of the corner portions of said partitions.

Figure 10 is a horizontal sectional view taken about on the line 10—10 of Figure 6 showing the six compartment form of key holder such as illustrated by all of the views heretofore referred to and described in detail.

Figure 11 is a cross sectional view similar to Figure 10 but showing a two spring, so called, type of six compartment holder.

Figure 12 is a view similar to Figure 10 but illustrating a six compartment holder in which five springs are employed for maintaining the holder body under tension; also a somewhat different arrangement of the intermediate partitions in relation to said springs.

Figure 13 shows a modification of my invention, the figure being a section similar to Figure 10 involving a six compartment type of holder in which a single spring of flat form is utilized.

intermediate the longitudinal end plates in the casing of the holder.

Figure 14 is a view similar to Figure 10, the holder construction involving the use of two compartment separating springs, and a single partition member dividing the holder into four key compartments.

Figure 15 is an end view showing one of the key exit and entrance ends of the holder, the latter being of the type shown in Figure 14.

Figure 16 is a view somewhat similar to Figure 6 showing the holder in the condition thereof when the edges are pressed together somewhat against the tension of the springs normally holding these edges at their limit of separating movement, and further showing a key displaced from its key compartment after the manipulation of the holder so as to flip the key out of such compartment.

Figure 17 is a view looking toward the end of the holder when the latter is adjusted to the position as shown in Figure 16 in which the key of the middle compartment has been displaced therefrom, the key being one of those disposed in the two opposite middle compartments.

Figure 18 is a view partly in section and partly in elevation showing primarily the tension plates used at opposite edges of the holder interiorly thereof, one of the spring members normally under compression or ready for compression by the simultaneous pressure on the edges of the holder, and illustrating the disposition of the key hooks, two of which are directly attached to each of the springs, one of which is shown in the view.

Figure 19 is a view looking endwise toward the tension plates and brings out the manner in which the three springs of the six compartment holder illustrated in Figures 1 to 10 of the drawings primarily, are mounted upon the said plates; and also showing how the six key hooks carried by their respective chains are attached to the said spring members.

I now proceed to describe the detailed construction of my invention as it is disclosed essentially in Figures 1 to 10 and Figures 18 and 19 of my drawings, Figure 16 being equally applicable insofar as it shows corresponding features of my construction to those referred to in the figures previously mentioned.

My holder comprises a body in the form of a casing 1 which I prefer to make of leather material or any material equivalent thereto. Rubber or flexible plastic substances may also be used and under some conditions would be advantageously employed. Preferably a single piece of leather or like material is formed to provide the casing 1, the end portions of the material being joined by means of suitable rivets such as designated at 2, one of the ends of the material overlying the other. As seen best in Figures 6 and 16, there are secured on the inner faces of the edge portions of the casing 1 the curved metal plates 3, said plates being substantially concavo-convex formation in cross section. The plates are attached to the casing by the upper and lower rivets designated 4, one of which is shown best perhaps in Figure 7, greatly enlarged.

Attached to the inner faces of the sides of the casing 1 and secured at the opposite ends thereof to the opposite ends of said sides by rivets 5 are the facing members 6 which are preferably made of cloth material though very thin leather might be substituted if so desired. Also if desired these facing members may be additionally

attached to the inner faces of the casing sides by stitching though the latter is not illustrated and does not have to be employed. The facing members 6 have peculiar utility in providing closure means for one end of each compartment of the holder in which a key may be disposed, as later more fully pointed out.

In the six compartment type of holder which is now being described, my construction contemplates the use of two partition members which are referred to by the number 7. Each of these partition members is of substantially the form illustrated in Figure 9. It consists of a body sheet of flexible material such as cloth or the like, and is formed at its corner portions with lateral extensions 8 apertured to receive certain of the rivets 4 previously mentioned as attaching the spring mounting plates 3 to the ends of the casing. In other words in respect to each of the partitions 7, the extensions 8 at one vertical edge will be penetrated by the two rivets 4 at opposite ends of the holder, and the extensions 8 of the adjacent partitions 7 extending in opposite directions of those of the previously mentioned partition will be similarly penetrated and clamped by the same rivets 4. Figure 7 clearly illustrates the foregoing feature of my invention and the manner in which the extensions 8 of the two intermediate partition members 7 are curved laterally toward each other in order to be properly engaged by the rivet means 4 for proper attachment to the end portions of the casing 1.

The opposite ends of the partition members 7 have secured thereto as seen clearly in Figures 4 and 5 resilient members 9, two of such members being stitched or otherwise attached at opposite sides of each end of the individual partitions 7. The members 9 are in the nature of obstacle means, flanges, or protrusions laterally from the plane of the partition members 7, acting to provide a resilient mouth portion for the exit and entrance opening between the partitions 7 and the facing members 6 of the holder. Preferably the end members 9 project slightly from the key entering and exit ends of the holder casing 1 and the parts 6 and 9 lie in substantial contact with one another normally or very closely spaced from one another.

I now refer to Figures 4, 5, 6, 16, 18 and 19 of my drawings in reference to the provision of novel spring devices included in my holder construction, which spring devices maintain the holder in its normal condition for receiving and holding the keys while the holder is in the pocket of the user, his purse or elsewhere. The spring devices consist of S-shaped spring members, each of which will be indicated as comprising the spaced or opposite legs 10, pocket closing cross portions 11, and pocket closing and spacing intermediate bridge portions 12. On each spring member the chain of a key hook will have its free end link threaded to attach said chain, designated 13, to one of the cross portions 11 of the member. Each chain 13 will carry a customary form of key holding hook 14. The chains 13 will be engaged with the cross portions 11 of each spring member preliminarily, after which the leg portions 10 of the spring member will be spot welded, soldered, or otherwise rigidly secured in the concave portion of an associated one of the plates 3, in a direction in line with the longitudinal axis of these plates.

As seen in Figure 19 of the drawings, quite clearly, for a six compartment key holder of the

type being described, three of these spring members are used, and their legs are spot welded or attached to the parts 3 in spaced relation, said legs all being parallel with one another and with the plates 3. The outer springs or spring members as distinguished from the inner or intermediate spring member, are disposed, each between the facing at 6 and one side of the casing 1. The inner or intermediate spring member on the other hand is located between the partition members 7. The mounting of the spring members is such that practically all portions of each spring member including the parts 10, 11, and 12 are along side and parallel with the adjacent spring members. The effect of the said arrangement of the spring members is to cause the closing portions 11 of the three members to engage with the facing members 6 and the partition members 7 to hold these parts in close contact so that in conjunction with the correspondingly associated bridge members 12 of the spring members, a tapering series of compartments closed at the inner narrow end portions, see Figure 6, will be provided on each side of a line medially and longitudinally of the holder. Each compartment of each of the series comprising three compartments opens toward the end of the holder casing 1 nearer the larger end of the compartment. In other words each of the compartments provided for the keys may be said to be closed at one side by the associated plate 3 and leg 10 of the spring, the closing portion 11 and bridge portion 12 of each spring member acting in cooperation with the adjacent portions of the spring member adjacent thereto, due to the clamping effect of said portions on the partitions 7 and facing members 6, to close the other side and inner end of the other compartments.

In addition to the function above ascribed to the spring members in affording division means for segregating the several key compartments of my holder, said spring members perform the separate function of normally maintaining the casing 1 of my holder in what may be characterized as its normal or extended condition as illustrated in Figures 1, 3 and 6 as distinguished from the condition of the holder as seen in Figure 16, wherein the opposite edge portions 15 of the holder are compressed slightly toward each other for facilitating key ejection. In other words I avail of the spring members comprising the parts 10, 11 and 12 for normally holding the edge portions 15 of the casing 1 separated to a pre-determined limit of movement. The said edge portions may be maintained under slight tension by reason of the spring bearing effect of the spring members at the leg portions 10 thereof against the inner sides of the plates 3, but said spring members have sufficient resiliency to readily permit the squeezing or compressing toward one another of the edge portions 15 of the casing in the operation of displacing a key or re-entering the key in relation to its particular key compartment.

It is notable that in a six key compartment holder such as I have described, three of the key compartments located side by side will open toward the upper open end of the casing 1 and are adjacent to one of the ends designated 15, while the other three compartments are located adjacent to the other end of the casing 1 and open in an opposite direction toward the other open end of the casing. The materials of the facing members 6 and the partition members 7 are so snugly clamped or held together along the line of adjacency of the parts 11 and 12 of the

shaped spring members that the chains 13 which carry the hooks 14 will be freely held on the cross portions 11 of the spring members with which they are connected and will not become displaced laterally from such cross portions.

The use of my key holder, and its method of operation, are substantially the same as in respect to the key holder of my previously identified patent.

The manner of removing a key from a compartment in the holder, assuming the keys are arranged substantially as depicted in Figure 6 of the drawings, may be briefly described as follows. The user of the key holder will grasp the same much after the manner illustrated in Figure 16 and by pressing on the closed edges 15 of the casing near the upper open end by means of the thumb and second, third and fourth fingers, the said closed edges 15 may be moved toward each other. Meanwhile by using the index finger of the same hand grasping the holder, a selected one of the compartments to be opened in the above operation may be additionally separated by movement of the index finger thereto, and by flipping the holder upwardly the key in the right hand compartment as shown in Figure 6 may be displaced from said compartment after the manner illustrated in Figure 16. This operation applies if the index finger is introduced into any one of the three key pockets or compartments at the upper end of the casing as shown in Figures 6 and 16. To eject any one of the keys in the lower compartments as shown in Figures 6 and 16 the user will of course invert the holder from the positions shown and by proper selecting with the index finger the particular compartment in which a key is to be displaced, the holder may be flipped upwardly and the key thrown from its position in a very simple manner so as to be ready to be grasped and used for unlocking a particular door or any other locked place on which the key is to be used. Practically speaking, the replacement of the key may be effected by mere reverse of operation as previously described. In other words, it being assumed that while the key designated 16 has been displaced from its proper compartment or pocket of the holder, has been used, and is ready to be replaced in the holder, all the user has to do is again press on the closed edges 15 of the holder near the end where the key pocket is located, using his index finger to spread the sides of the pocket slightly in addition to the spreading accomplished by the pressure on the ends 15, and then by flipping the key backwardly, it may be caused to drop back into its pocket ready to be contained by the holder for future use.

I now refer briefly to certain modifications of my invention. In Figure 11, the construction of my holder is very much the same as previously described but I am enabled by the proper positioning of the spring members, two of which are used only, to dispense with one of the spring members notably the middle one of the unit. The two spring members that are employed comprising the parts 10, 11, and 12 as before described will be located intermediate the facing members 6 and the outer faces of the adjacent partition members 7 and closely enough spaced to cause the longitudinal middle portions of the said partition members 7 to be clamped together to create the middle pocket for the key members disposed therein.

In Figure 12 the modification of construction

varies from the first described construction in that I utilize five of the S-shaped spring members. In the Figure 12 construction the two additional spring members are located between the adjacent sides of the two facing members 6 and the two partition members 7. When using the construction of Figure 12 the lighter form of S-shaped spring member may be availed of, the combined compressive force needed to be exercised on the five springs by pressure of the closed edges 15 of the casing 1 together, being about equal to that necessary to be exerted upon the larger cross section spring members utilized in the construction of Figures 1 to 10 inclusive.

In Figure 13 I show how it is possible in the carrying out of my invention to utilize a single S-shaped spring member designated 17, and shown in sectional view only, for the purposes of my holder. This spring member 17 will preferably be made of elongated or flat cross section to provide the necessary strength or resiliency of the same and the bridge portion of the spring member designated 18 will be located between the two partition members 7, together with the portions of the members 17 that correspond with the portions 12 of the previously described spring members. In the construction of Figure 13 it is necessary to stitch the facing members 19 to the partition members designated 20 at the points marked 21, thus forming a sort of pocket which encloses the bridge member 18 of the spring member.

Figures 14 and 15 illustrate a construction which is very similar to that first described by me herein except that I utilize only two S-shaped spring members 22, and a single partition member 23, the spring members being located to cause the facing members 24 to belly toward each other by the action of the bridge portions 25 interposed between the sides of the casing 1 of said facing members 24. This arrangement of the parts 25 causes them to clamp against the vertical or middle portion of the partition member 23 and to hold the facing members 24 in close contact with the adjacent portions of said partition member. The spaces for the key pockets are readily circumscribed by the adjacent wall portions of the parts 23 and 24 in a self-evident manner and four key pockets containing the keys 16 are provided. The partition member 23 will be equipped with the resilient edge protrusions 26 which correspond with the members 9 previously described.

The effective action of the protruding resilient members 9 and 26 will be quite apparent upon reference to Figures 4 and 5 and Figures 8 and 15 of my drawings. These members 9 and 26 provide ledges or extending flanges which are sufficiently close together, or even held in contact, if desired, so that there is no liability of a key or keys 16 being accidentally displaced from the proper pocket or pockets in which it or they are received by any accidental pressure exerted on the end members 15 of the casing 1. The members 9 and 15, effectively speaking moreover, provide clamping parts which encompass the casing or container 1 at the end openings thereof and owing to the nature of the material, leather, rubber, or the like, from which these members 9 and 15 are made, they act in a measure as resilient enclosing means or closing members at each open end of the casing 1 of the holder.

It will be obvious from the foregoing that I may construct my key holders in different forms

such as proposed in the preferred construction described herein and the various modifications thereof, and the number of compartments of my key holder may be varied in accordance with the constructional technique employed as set forth, and largely involving the use of a greater or less number of S-shaped springs comprising the parts 10, 11, and 12.

Having thus described my invention, what I claim as new and desire to secure by Letters Patent of the United States, is:

5. In a key holder, a casing comprising spaced side portions forming a key space open in at least one direction from such space, and a longitudinally compressible spring member in the casing engaged with the inner end walls thereof and separating the said space into key compartments normally maintained closed by the expansive force of said spring.
10. 2. In a key holder, a casing comprising spaced side portions forming a key space open in opposite directions from such space, side by side arranged spring members in the casing engaged with inner walls thereof to normally yieldably hold the latter limitedly spaced, and a partition between said spring members coacting with the latter to divide the space into a plurality of key compartments.
15. 3. A holder as claimed in claim 2, in which the spring members are of S-shape to cause certain key compartments to open in one direction from the key space, and other key compartments to open in an opposite direction.
20. 4. A key holder as claimed in claim 1, in which the spring member is formed to provide adjacent separated key compartments opening in opposite directions.
25. 5. A key holder as claimed in claim 1, in which the spring member is formed to provide oppositely extending connected U-shaped portions opening in opposite directions and forming key compartments in the casing, and facing members applied to the inner faces of the sides of the casing on opposite sides of the spring member.
30. 6. In a key holder, a casing comprising spaced side portions forming a key space open in opposite directions from such space, side by side arranged spring members in the casing engaged with its walls to normally yieldably hold the latter limitedly spaced, and a partition between said spring members coacting with the latter to divide the space into a plurality of key compartments, and facing members applied to the inner faces of sides of the casing at the outer sides of said spring members.
35. 7. In a key holder, a casing having spaced sides provided with closed edge portions compressible toward each other, and spring members holding the edge portions apart, and separating the casing into key compartments having entrances at at least one end of the casing.
40. 8. A key holder as claimed in claim 7, combined with a partition between the spring members united to the ends of the casing, and protruding resilient members on the partition adjacent to the ends of the casing at said key compartment entrances.
45. 9. In a key holder, a casing having spaced sides and closed edge portions, the latter compressible toward each other to spread the sides, the top and bottom of the casing being open to provide key entrance and exit portions, the casing being made of flexible material, and spring members engaging inner walls of the casing and yieldable to permit spreading of the casing sides.

10. In a key holder, a casing having spaced sides and closed edge portions, the latter compressible toward each other, and spring members holding the edge portions apart, and separating the casing into key compartments having entrances at the top and bottom of the casing, pressing of the edge portions of the casing being adapted to spread the sides apart, and flexible closure elements between the sides at the top and bottom of the casing adapted to spread on pressing the edge portions toward each other, combined with a partition between the spring members and carrying said flexible closure elements at opposite sides adjacent the top and bottom of the holder, the spring members being of S-form having the extremities attached to the inner walls of the casing at said edges and establishing the said key compartments.
